6 Claims. (Cl. 242—75)

This invention deals with the arrangements for supporting flat coils of flexible strip material, for instance paper, which is drawn off from the coils under tension. In arrangements of the kind to which the invention relates the tension is controlled by friction applied to one or both of the sides of the coil of material due to a pressure tending to move nearer together the two discs or frames or other members (hereinafter for convenience referred to as discs) between which the coil is carried. The object of the invention is to so arrange the control of the tension that it remains approximately constant in value as the strip is drawn off and the size of the coil is diminished. This object is attained by arranging that the lateral pressure is applied so as to act only on the outer part of the coil at all stages of the drawing off. This is done by making one or both of the discs with a dished inner surface so that this surface is not parallel with the corresponding surface of the other disc so that the only part of the coil (which has parallel sides owing to the uniform width of the strip) gripped by the two discs is that part in the immediate neighbourhood of the outer periphery from which the strip is being drawn off. One of the discs may be held stationary while the other is mounted so that it can rotate with the coil, a spring for example, being employed to press the dished disc against the coil, the dished disc being arranged to move towards the fixed disc as the diameter of the coil becomes reduced.

The action may be assisted by lining one of the discs with a layer of yielding material, such as felt, which is free to move relative to the disc. On the other hand, both devices may be allowed to rotate with the coil, the lateral pressure being obtained as before by means of a spring. In addition to this spring a relatively weak spring may be used. The lateral pressure produced by this spring is a comparatively light one and has only a small effect compared with the main pressure during the earlier stages of the unwinding, but during the later stages, its comparative effect upon the coil increases, when the main pressure is reduced due to the relative movement of the discs towards each other. The invention may be used with one or more coils.

Three forms of construction in accordance with the invention are illustrated as examples in the accompanying drawings, wherein:—

Fig. 1 is a sectional elevation of one form of construction.

Fig. 2 a similar view of a modified form and

Fig. 3 a similar view of a further modification. In Fig. 1 a flat disc 1 is secured by means of the bolts 2 and nuts 3 to a convenient support 4. The central part of the disc 1 is formed with stepped portions 5 and 6. The stepped portion 5 has secured to it a bush 7 upon which a centre 8 for the coil 9 can rotate as the material is drawn off from the coil. The stepped portion 6 has a bearing member 10 secured to it and which supports a dished disc 11, the latter being provided with a sleeve or bush 12. The bearing member 10 has a hollow extension 13 which is screw-threaded externally and internally. The dished disc 11 is maintained in position by means of a nut 14 which is recessed to receive a ball bearing 15, and a spring 16 interposed between the dished disc 11 and the ball bearing 15. The nut is prevented from rotating by a lock nut 17. A felt washer 18 may be placed against the flat disc 1 and rotate with the coil 9. The spring 16 applies the necessary pressure to the dished disc 11 and the dishing of the latter ensures that the pressure is always applied to the periphery of the coil irrespective of the diameter of the latter. The desired degree of pressure may be regulated by the nut 14. As the coil 9 rotates its outer layers are pressed by the dished disc 11 against the yielding surface of the felt washer 18 and the greater part of the frictional resistance resulting from the lateral pressure will always act at a radius which is approximately the radius of the outside of the coil. This tends to make the tension more nearly constant than would be the case if the disc 11 had a flat inner surface. Moreover owing to the fact that the inner surface of the disc 11 is dished, as the diameter becomes reduced, during the unwinding of the coil, the spring 16 causes the dished disc 11 to approach the fixed disc 1, and so reducing the pressure produced by the spring 16. This is of advantage for the following reason. In addition to the friction due to the lateral pressure there is a further resisting friction due to the pressure between the centre 8 upon which the coil 9 is mounted and the bush 7 or stepped portion 5 on which the coil rotates. The importance of this component of the total resistance increases as the diameter of the coil decreases, and it is therefore desirable that the friction due to the lateral pressure should be falling off more rapidly than the diameter decreases. This effect is produced by arranging the spring to function as described above.

In Fig. 2, two coils 9 are shown arranged side by side upon a common hub 19 and as the ar-

rangements are the same for both coils, those for one of the coils only will now be described. The coil 9 is mounted upon a centre 8 between a dished disc 11 and a flat disc 1. The latter is secured to a ring 20 and the ring can rotate upon the hub 19. The central portion of the outer surface of the flat disc 1 is recessed to receive a felt washer 21 which rotates with the flat disc 1 and is held in position by a metal ring 22. The hub 19 is screw threaded so that a nut 23 can be used to hold the flat disc 1 in position. The dished disc 11 is supported upon a sleeve 24 which is keyed to the hub 19 so that it cannot rotate upon the hub but can slide along the hub. A spring 16 is housed in a recess 25 in the end of the hub 19 and presses against the sleeve 24. A felt washer 26 which rotates with the dished disc 11 is interposed between the outer surface of the dished disc 11 and the sleeve 24. A ring 27 holds the washer 26 and sleeve 24 in position and a ring 28 holds the ring 22 and washer 21 in position. In this case both discs rotate and the requisite restraint upon the coil against rotation is produced by the pressure exerted by the spring, and acting at the outer part of the coil and the friction between the stationary rings and the felt washers disposed between the rings and the discs. As the coil 9 becomes reduced in diameter during the unwinding process, the spring 16 presses the dished disc 11 towards the flat disc 1. The pressure exerted by the spring 16 can be adjusted by the nut 23. In the case of the outer coil an abutment for the spring may be provided in the form of a ring 29 which may be adjustable longitudinally of the hub 19 but is prevented from rotating.

Fig. 3 shows two coils 9 mounted upon a screw threaded spindle or hub 30 having a keyway 31. Each coil has a centre 8 and the coil can rotate upon a ring or sleeve 32, the latter being screwed on to the flat disc 1 which can also rotate. The latter is recessed to receive a felt washer 33 which rotates with the flat disc 1 and is held in place by a stepped metal ring 34. The dished disc 11 can rotate upon a flanged metal ring 35 and a rotatable felt washer 36 is interposed between the ring 35 and dished disc 11. The rings 34 and 35 are keyed to the hub 30 so that they cannot rotate but can slide along the hub. A relatively weak spring 37 presses against the ring 35 and a stronger and stiffer spring 16 is interposed between the spring 37 and a ring 38 secured to the end of the hub 30. The stepped ring 34 is used to support the dished disc 11 for the outer coil 9 and a rotatable felt washer 38' is placed between the stepped ring 34 and this dished disc. The outer coil 9 is carried upon a sleeve 32 as in the case of the first coil and a rotatable felt washer 39 is placed between the flat disc for the outer coil and a ring 40 keyed to the hub 30. A nut 41 holds the two coils in position upon the hub 30 and controls the pressure exerted by the springs 16 and 37.

In this construction, the lateral pressure upon the coils is produced by the two springs, but the weaker spring 37 has a small effect only as compared with the main pressure produced by the other spring 16 during the earlier stages of the unwinding of the coils. During the later stages, however, the comparative effect of the weaker spring 37 upon the coils is increased, when the main pressure is reduced owing to the movement of the dished disc 11 towards the flat disc 1. This construction has the advantage of steadyng

the tension upon the coils should there be any tendency for it to fluctuate during the later stages of the unwinding when the diameters of the coils are comparatively small. The necessary frictional restraint against rotation of the coils is produced as in the previous case by the spring pressure acting at the outer parts of the coils and the friction between the various stationary rings and their respective felt washers. Instead of employing the particular arrangement of springs as described with reference to Fig. 3 the dished disc itself might be formed as a springy member arranged to exert the major portion of the lateral pressure upon the coil during the earlier stages of the unwinding process, this pressure decreasing as before as the diameter of the coil was reduced. A weaker spring would then be arranged to move the disc along the hub and to have an increased comparative effect upon the coil during the later stages of the unwinding process. This arrangement might be employed with one or more coils.

What I claim as my invention and desire to secure by Letters Patent is:—

1. A device for controlling the tension of strip material as it is being drawn off from a flat coil comprising a carrier for the coil having two discs, one of which has a dished inner surface so as to make contact with the coil at the radially outer part of the latter, one of said discs being axially movable relative to the other, a fixed abutment, a relatively stiff spring and a weaker spring operating in conjunction between said abutment and the movable disc and tending to move the latter towards the fixed disc, the weaker spring being relatively ineffective during the earlier stages and relatively more effective during the latter stages of the unwinding of the coil than the stiffer spring.

2. A device for controlling the tension of strip material as it is being drawn off from a flat coil, comprising a carrier for the coil having two discs, one of which has a dished inner surface, and one of which is movable axially relative to the other, a fixed abutment, a spring acting between the fixed abutment and the axially movable disc to press the dished disc and the coil into contact with each other at the radially outer part of the coil, and the coil towards a fixed part of the carrier, so as to exert a braking action upon the rotation of the coil, the force exerted by the spring and the braking action upon the coil being reduced as the size of the coil is reduced.

3. A device for controlling the tension of strip material as it is being drawn off from a flat coil, comprising a carrier for the coil having two discs, one of which has a dished inner surface, and one of which is axially movable relative to the other, a fixed abutment, a relatively stiff spring and a weaker spring operating in conjunction between the abutment and the axially movable disc to press the dished disc and the coil into contact with each other at the radially outer part of the coil, and the coil towards a fixed part of the carrier to exert a braking action upon the rotation of the coil, the weaker spring being relatively ineffective in its action upon the axially movable disc during the earlier stages of the unwinding of the coil than the stiffer spring, and relatively more effective during the later stages of the unwinding of the coil as compared with the effect produced by the stiffer spring.

4. A device for controlling the tension of strip

material as it is being drawn off from a flat coil comprising a coil carrier adapted to make a comparatively close fit with the coil and having two discs between which the coil is adapted to be placed, and one of the discs having a dished inner surface so as to make contact with the coil only at the radially outer part of the latter, and means for applying a gradually reducing lateral pressure to the coil through the discs.

5 10 15 5. A device for controlling the tension of strip material as it is being drawn off from a flat coil, comprising a coil carrier having a rotatably fixed disc, a freely rotatable second disc having a dished inner surface, one of said discs being axially movable, an axially fixed abutment and a spring interposed between the said abutment and the axially movable disc.

6. A device for controlling the tension of strip material as it is being drawn off from a flat coil, comprising a carrier for the coil having a rotatable but axially fixed disc, and a rotatable and axially movable disc, one of said discs having a dished inner surface, said axially movable disc approaching said axially fixed disc as the coil diameter is reduced, a fixed abutment, a spring interposed between the fixed abutment and the axially movable disc and exerting pressure upon the latter, the spring elongating and exerting a reducing pressure upon the axially movable disc as the latter moves towards the axially fixed disc, a friction member, and means for maintaining the friction member bearing against the axially fixed disc.

FRANCIS HENRY FRY.
